UNITED STATES PATENT OFFICE

155,975

DESIGN FOR A CONDIMENT SHAKER

Clyde Duley, Sherman, Tex., assignor of twenty-five per cent to Melvin B. Dunham and fifty per cent to Murray A. Love, Sherman, Tex.

Application May 28, 1948, Serial No. 146,659

Term of patent 7 years

(Cl. D44—22)

To all whom it may concern:

Be it known that I, Clyde Duley, a citizen of the United States, residing at Sherman, in the county of Grayson and State of Texas, have invented a new, original, and ornamental Design for a Condiment Shaker, of which the following is a specification, reference being had to the accompanying drawing, forming part thereof.

The dominant features of the design reside in the portions shown by full lines.

I claim:

The ornamental design for a condiment shaker, as shown and described.

CLYDE DULEY.
